(57) **CLAIM**

The ornamental design for a cremation urn, as shown and described.

DESCRIPTION

FIG. 1 is a top perspective view of a cremation urn showing my new design;

FIG. 2 is a bottom perspective view of the cremation urn of FIG. 1;

FIG. 3 is a front view of the cremation urn of FIG. 1;

FIG. 4 is a top left perspective view of the cremation urn of FIG. 1;

FIG. 5 is a bottom left perspective view of the cremation urn of FIG. 1; and,

FIG. 6 is a top left perspective view of the base of the cremation urn thereof, shown separately for ease of illustration.

The broken lines on the cremation urn base and the broken line showing of the removable cover at the base of the cremation urn are for the purposes of illustrating environmental structure and form no part of the claimed design.
